(57) CLAIM

The ornamental design for baby support apparatus, as shown and described.

DESCRIPTION

FIG. 1 is a perspective view of a baby support apparatus, showing my new design;

FIG. 2 is a top plan view thereof;

FIG. 3 is a bottom plan view thereof;

FIG. 4 is a side elevation view thereof;

FIG. 5 is a front elevation view thereof; and,

FIG. 6 is a back elevation view thereof.
